United States Patent Office

Des. 196,175
Patented Sept. 3, 1963

196,175

TRUCK

Donald B. Warner, Northfield, Ill., assignor to Warner
Electric Company, Inc., Chicago, Ill., a corporation of Illinois

Filed May 14, 1962, Ser. No. 70,113

Term of patent 14 years

(Cl. D14—3)

The dominant features of my design reside in the portions shown in full lines.

I claim:

The ornamental design for a truck, substantially as shown and described.
